UNITED STATES PATENT OFFICE.

FRED K. HENDRICKSON AND SIGURD H. HELLAND, OF WHITINSVILLE, MASSACHUSETTS, ASSIGNORS TO WHITIN MACHINE WORKS, OF WHITINSVILLE, MASSACHUSETTS, A CORPORATION OF MASSACHUSETTS.

SAFETY GUARD FOR TWISTING MACHINES.

Application filed April 17, 1926. Serial No. 102,664.

Our invention has reference to twisting machines and more particularly to safety devices for such machines, and the invention consists of a guard which is arranged and 5 adapted to cover the entrance to the place of danger to the operative at the intersection of the peripheries of the top and bottom rolls. In twisting machines the operative 10 in the performance of her duties is quite liable to insert her fingers in too close proximity to the "bite" of the delivery rolls, with the result that it not unfrequently happens that her fingers are caught and drawn between the rolls and seriously injured thereby. 15 The object of our invention is to introduce into the construction of the machine a simple but effectual guard whereby it is impossible for the operative to receive injuries while the machine is in operation. 20 A preferred embodiment of our invention is described below in connection with the drawings forming a part hereof, and the distinguishing features of the invention are more particularly pointed out in the 25 appended claims.

In the drawings, Figure 1 is a fragmentary front elevation of a portion of a twisting machine showing our improved safety device applied thereto; Figure 2 is a plan view of Figure 1 and Figure 3 is an enlarged vertical transverse section on line 3-3 of Figure 1 showing the line of passage of the yarn through the delivery rolls to the receiving spool. 30

Referring to the above figures, it will be understood by those familiar in this art that twisting machines as usually constructed comprise a line of delivery rolls driven by suitable means (not shown in 35 drawings) and a line of top rollers superimposed on the driving roll and frictionally driven therefrom. The driving roll 10 is rotatable in bearings 11 formed in the supporting stands 12 fixedly connected to the 40 framing 13 of the machine. From four to eight top rolls 14 coact with each section of driving roll and are held in proper position thereon by their journals projecting into bearings formed in the fingers 15 of the

cap-bar 16 detachably mounted in bearings 50 17 located in the upper part of the supporting stands 12.

Projecting from the outer end of each finger 15 is a downwardly extending guard 18 of an inverted T-shaped form, the horizontal portions 19 of which are so located as to cover the intersection of the peripheries of two adjacent top-rolls, with that of the driving roll. A space 20 is provided between the ends of two adjacent guards for the 55 passage of a thread 21 by the operative in the act of "piecing-up" after a breakage of the thread.

By this construction it is impossible for the operative's fingers being caught in the 60 "bite" of the rolls thus averting possible 65 serious injury to the operative.

We claim:

1. In a machine of the character described, 70 in combination, a driving drawing roll, a plurality of top-rolls superimposed on said driving roll and frictionally driven thereby, bearing stands for supporting said driving roll, a cap-bar supported between said stands, a plurality of fingers on the cap-bar each finger positioning two adjacent top-rolls on the driving roll, and means attached to each finger for covering the intersection of the peripheries of the rolls. 75

2. In a machine of the character described, 80 in combination, a driving drawing roll, a plurality of top-rolls superimposed on said driving roll and frictionally driven thereby, bearing stands for supporting said driving roll, a cap-bar supported between said stands, a plurality of fingers on the cap-bar each finger positioning two adjacent top-rolls on the driving roll, an extension 85 to each finger of an inverted T-shaped form, the horizontal portions of which guard the intersection of the peripheries of the rolls, and a space between adjacent guards for the 90 passage of the thread.

In testimony whereof we have signed this specification.

FRED K. HENDRICKSON.
SIGURD H. HELLAND.
